CLAIM

The ornamental design for a mobile cellular phone antenna cover, as shown and described.

DESCRIPTION

FIG. 1 is a perspective view of the mobile cellular phone antenna cover, showing my new design;
FIG. 2 is a front view;
FIG. 3 is a left side view;
FIG. 4 is a bottom view;
FIG. 5 is a rear view;
FIG. 6 is a right side view; and,
FIG. 7 is a top view.

The broken line showings of FIG. 1 are for illustrative purposes only and form no part of the claimed design.
